Patented Oct. 26, 1965

202,652

ORNAMENTAL METALWORK PANEL

Gene W. Owens, Fort Worth, Tex., assignor to McKinley
Iron Works, Fort Worth, Tex., a partnership

Filed Oct. 28, 1964, Ser. No. 32,388

Term of patent 14 years

(Cl. D54—2)

FIG. 1

FIG. 2

FIG. 3

FIG. 4

FIG. 5

FIG. 1 is a side elevation of one side of an ornamental metalwork panel embodying my new design.

FIG. 2 is an elevational view of the opposite side of the panel.

FIG. 3 is a perspective view.

FIG. 4 is an end edge view of the panel, and

FIG. 5 is a similar view looking at the long edge of the panel.

I claim:

The ornamental design for an ornamental metalwork panel, as shown.
